CLAIM

The ornamental design for a clip-on label for intravenous systems, as shown and described.

DESCRIPTION

FIG. 1 is a perspective view of a clip-on label for intravenous systems in an open position, showing the new design; FIG. 2 is a top view thereof;

FIG. 3 is a bottom view thereof;

FIG. 4 is a front view thereof;

FIG. 5 is a back view thereof;

FIG. 6 is a left view thereof;

FIG. 7 is a right view thereof;

FIG. 8 is a front perspective view thereof in an environment of use;

FIG. 9 is a back perspective view thereof in an environment of use;

FIG. 10 is a top view shown in a closed position;

FIG. 11 is a bottom view thereof;

FIG. 12 is a front view thereof;

FIG. 13 is a back view thereof;

FIG. 14 is a left view thereof;

FIG. 15 is a right view thereof; and,

FIG. 16 is a front view thereof shown in an environment of use.

The broken lines in the drawings show environment and form no part of the claimed design.

1 Claim, 8 Drawing Sheets
